[57] CLAIM

The ornamental design for a combined chair and tray, as shown and described.

DESCRIPTION

FIG. 1 is a front perspective view of the combined chair and tray showing my new design;
FIG. 2 is a top plan view thereof;

FIG. 3 is a left side elevational view thereof;

FIG. 4 is a front elevational view thereof;

FIG. 5 is a right side elevational view thereof; and

FIG. 6 is a rear elevational view thereof.

The bottom of said chair and tray is unornamented.
